Primary Examiner—Susan Moon Lee(74) *Attorney, Agent, or Firm*—Katten Muchin Rosenman LLP(57) **CLAIM**

I claim the ornamental design for a pet toy, as shown and described.

DESCRIPTION

FIG. 1 is a perspective view of a collapsible feed dispenser of the present design in which the carrying straps are shown stood on one end;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the drawings are not claimed.
